Primary Examiner — T Chase Nelson*Assistant Examiner* — Jonathan J. Han*(74) Attorney, Agent, or Firm* — Fox Rothschild LLP(57) **CLAIM**

The ornamental design for a firearm handguard, as shown and described.

DESCRIPTION

FIG. 1 is a top, rear, left perspective view of a firearm handguard according to the present disclosure.

FIG. 2 is a left side view of the embodiment of FIG. 1.

FIG. 3 is a right side view of the embodiment of FIG. 1.

FIG. 4 is a rear view of the embodiment of FIG. 1.

FIG. 5 is a front view of the embodiment of FIG. 1.

FIG. 6 is a top view of the embodiment of FIG. 1; and,

FIG. 7 is a bottom view of the embodiment of FIG. 1.

The broken lines in the Figures illustrate portions of the article that form no part of the claimed design.

1 Claim, 3 Drawing Sheets(56)
